US0D1073123S

(12) **United States Design Patent** (10) **Patent No.:** **US D1,073,123 S**
(45) **Date of Patent:** **** Apr. 29, 2025**

(54) **ACCESS CONTROL GATE**

(71) Applicant: **Magnetic Autocontrol GmbH**,
Schopfheim (DE)

(72) Inventor: **Timo Rauer**, Rheinfelden (DE)

(73) Assignee: **Magnetic Autocontrol GmbH**,
Schopfheim (DE)

(**) Term: **15 Years**

(21) Appl. No.: **29/821,999**

(22) Filed: **Jan. 5, 2022**

Related U.S. Application Data

(62) Division of application No. 35/510,369, filed on Jul. 29, 2019 (U.S. filing date under 35 U.S.C. 384), and having an international filing date of Jul. 29, 2019, now abandoned.

(30) **Foreign Application Priority Data**
